COMMUNICATIONS CORDS AND METHODS OF MAKING THEM

Bruno A. Raetsch, Lincoln Park, Pa., assignor to Western Electric Company, Incorporated, New York, N. Y., a corporation of New York

Application May 7, 1953, Serial No. 353,479

3 Claims. (Cl. 339—183)

This invention relates to communications cords and methods of manufacturing such cords, and more particularly to cords having plugs thereon used to make connections in telephone switchboards, and the like, and methods of manufacturing such cords.

The connection plugs on switchboard cords used in telephone exchanges must be ruggedly constructed to withstand being rapidly and repeatedly inserted into the jacks in the switchboards by telephone operators. In making connections the plugs are subjected to wear, stress and strain, which tend to make it necessary to replace them periodically. In manufacturing such plugs for the telephone industry, it has been necessary to employ considerable manual labor to assemble the many small parts of which the plugs are constructed. Consequently, a need has existed to simplify the construction and the method of manufacturing cords provided with such plugs.

An object of this invention is to provide new and improved communications cords and methods of making such cords.

Another object of this invention is to provide new and improved cords having telephone plugs thereon, and the like, and methods of making such cords.

A cord illustrating certain features of the invention may include a conductive tube mounted concentrically and in spaced relationship on a conductive center pin and within a conductive tubular shank of a plug body, a mass of plastic material molded in situ for separating the pin, the tube and the shank, said mass having sockets formed at one end thereof, into which a plurality of conductors at one end of a length of cordage are inserted to make electrical contacts with the pin, the tube and the shank, and a plastic shell molded around the conductors at the end of the cordage and around the adjacent portions of the cordage and of the shank.

A method illustrating certain features of the invention may include the steps of assembling a conductive tube on a conductive center pin and within a conductive tubular shank of a plug body, molding plastic between the center pin, the tube and the shank, then electrically connecting the center pin, the tube and the shank to a plurality of insulated conductors at one end of a cord, and molding a plastic shell around the conductors at the end of the cord and around the adjacent portions of the cord and of the shank.

A complete understanding of the invention may be obtained from the following detailed description of cords embodying the invention and methods of making such cords, when considered in conjunction with the appended drawings, in which:

Fig. 1 is a fragmentary elevation of a completed communications cord embodying the invention;

Fig. 2 is a side elevation of apparatus suitable for performing one step in a method of manufacturing the cord illustrated in Fig. 1;

Fig. 3 is an enlarged, vertical section of a portion of the apparatus shown in Fig. 2;

2

Fig. 4 is a fragmentary, vertical section taken along line 4—4 of Fig. 3 as it would appear if the apparatus in Fig. 3 were unsectioned;

Fig. 5 is an enlarged perspective view of a portion of the apparatus shown in Fig. 3 as it would appear if the apparatus in Fig. 3 were unsectioned;

Fig. 6 is an enlarged perspective view of a portion of a plug at an intermediate stage of its manufacture;

Fig. 7 is a longitudinal section of the plug portion illustrated in Fig. 6;

Fig. 8 is a vertical section of apparatus suitable for performing another step in the method of manufacturing the cord illustrated in Fig. 1; and

Fig. 9 is an enlarged view, partially in section, of a portion of the plug in another stage of its manufacture.

Referring to Fig. 1, there is shown one end of a communications cord having a plug designed generally by the numeral 10 attached to a length of flexible, braided cordage 12. The right hand end of the plug 10 is provided in the usual manner with a ball contact 14, which completes an electrical circuit when this end of the plug is inserted into a jack on a telephone switchboard (not shown). Surrounding the plug 10 near the ball contact 14 is a ring contact 16 which completes another circuit when the plug is inserted into the jack. A little further away from the ball contact 14, the plug 10 is provided with a cylindrical metallic shank 18 which makes a third connection with the jack for electrical circuits involving three conductors. The diameter of the shank 18 is somewhat larger than that of the ring contact 16, which in turn has a slightly larger diameter than the ball contact 14. The ball contact 14, the ring contact 16 and the metallic shank 18 are all composed of brass.

A collar 20, known in the trade as a "dead collar," is located between the ball contact 14 and the ring contact 16. The collar 20 approaches the size of the shank 18 in diameter, being larger than the ball contact 14 and the ring contact 16. The collar 20 functions as a bearing surface as well as a guide when the plug 10 is being inserted into the jack on a switchboard. Since this operation subjects the collar 20 to considerable wear, it is customary to construct it of Phosphor bronze, or of some other wear-resistant material, and to insulate the collar 20 from the rest of the plug 10. The collar 20 is separated from the ball contact 14 by an annular insulating washer 22, and from the ring contact 16 by another annular insulating washer 24. The washers 22 and 24 may be composed of any suitable insulating material, such as hard rubber.

When the component parts of the plug 10 are first assembled, they do not yet have the contours illustrated in Fig. 1. These contours are imparted to the plug in a profiling machine, in which portions of an incomplete plug are machined away to attain the final shape and dimensions of the plug. Before the profiling operation, the incomplete plug may have the appearance illustrated in Fig. 7, in which a generally cylindrical, brass tip 26 threadedly engages an end of a steel center pin 28, which extends axially through a brass tube 30 and protrudes beyond both ends thereof. An enlarged end 32 of the tube 30 is separated from the tip 26 by an insulating washer 34, a bronze ring 36, and another insulating washer 38, in the order given. The tube 30 is mounted concentrically within the cylindrical shank 18 with the enlarged end 32 thereof located beyond one end of the shank.

From a comparison of the incomplete plug shown in Fig. 7 with the finished plug shown in Fig. 1, it is seen that the tip 26 is eventually profiled to form the ball contact 14, the enlarged end 32 of the tube 30 is ma-

chined away to form the ring contact 16, the bronze ring 36 is profiled to produce the "dead collar" 26, and the outer peripheries of the washers 34 and 38 are machined to become the annular washers 24 and 22, respectively. In addition, an annular, hard rubber bushing 40 on the incomplete plug is profiled to become a bushing 42 separating the contact ring 16 from the cylindrical shank 18 on the finished plug.

The length of flexible cordage 12 contains a plurality of individually insulated conductors 43, 44 and 45, which respectively are electrically connected to the ball contact 14, the ring contact 16 and the cylindrical shank 18 when the plug 10 is attached to the end of the cordage. These connections are made through the center pin 28, the tube 30 and the rim of the shank 18, respectively. The conductors 43, 44 and 45 are first exposed at the adjacent end of the cord, and then the ends of the conductors are encircled by solderless terminals 46-46. Each of the terminals 46-46 is provided with a prong 48 (Fig. 9) which, when the terminal is wrapped around the end of the conductor, penetrates the insulation and makes electrical contact with tinsel conductors, of which a conductor 47 is shown, forming the cores of the insulated conductors. Each of the solderless terminals 46-46 is also provided with a flat tang 50, which protrudes beyond one end of the terminal in alignment with the longitudinal axis thereof.

The tanks 50-50 of the solderless terminals 46-46 are pushed into a plurality of sockets (Figs. 6 and 9), of which three designated 51, 52 and 53 are provided, to make electrical contacts with the shank 18, the center pin 28, and the tube 30. Although these sockets are not much higher than the thickness of the tangs 50-50, it is advisable to bend the tangs into a somewhat sinuous shape, as shown in Fig. 9, in order to make them contact snugly against opposite walls of the sockets, which walls are not identical in composition. In each case, one of the walls is composed of a molded plastic and the other wall is metallic. For example, in the case of the socket 51 shown in Fig. 9, the inner periphery of the metallic shank 18 forms one wall of this socket, and the opposite wall is formed by a molded plastic spacer 54. Thus, only one wall of each socket is electrically conductive.

The spacer 54 is tubular in shape, and it extends between the shank 18 and the tube 30 up to the bushing 40. A plastic spacer 55, similar in construction to the spacer 54, extends between the center pin 28 and the tube 30. The spacers 54 and 55 are both integral with a block 56 of molded plastic, which surrounds a portion of the center pin 28 projecting beyond one end of the tube 30. It may be said that the spacers 54 and 55 project from one end of a single mass of plastic material molded in situ, and the block 56 projects from the other end of this mass. Thus, the block 56 is a continuation of the spacer 55 beyond the tube 30 as well as a continuation of a segment of the spacer 54 on one side of the center pin 28.

The spacer 54 contains the sockets 51 and 53, with the socket 51 located on the outer periphery thereof next to the metallic shank 18 and the socket 53 located near the inner periphery thereof adjacent to the tube 30. The third socket 52 is formed in the block 56 and is adjacent to the center pin 28. These three sockets are spaced 120° apart about the axis of the center pin 28, and they are all situated on the same end of the plug 10.

The sockets 51, 52 and 53, the spacers 54 and 55, and the block 56 are all formed simultaneously by injecting molten plastic between the center pin 28, the tube 30 and the shank 18. This operation is performed in a two-part mold designated generally by the numeral 57 (Figs. 2 and 3). One part of the mold 57 is a generally rectangular member 58 having a sprue hole 60 formed in one side thereof for the admission of molten plastic into an interior mold cavity 62. The other part of the mold 57 is divided into two hinged sections 64-64, which are

generally frustoconical in shape when these sections are closed about the plug 10.

One end of the plug 10 in its incompletely assembled condition is inserted into the mold cavity 62, and the other end of the plug fits into the interior of the sections 64-64. At this stage of its manufacture, the cylindrical tip 26 has not yet been threaded onto the end of the center pin 28, the washer 38 is also missing, and the components of the plug 10 that are present have not yet been machined to their final shapes and dimensions. Due to the fact that this end of the plug 10 has an irregular shape at this stage of its manufacture, the mold sections 64-64 are hinged together to enable them to be closed snugly thereabout, while the other end of the plug can be merely slid into the member 58.

A holder 66 is provided with a generally frustoconical recess 68, which matches the shape of the mold sections 64-64 when they are closed. The holder 66 is designed to receive the mold sections 64-64 when they are closed about an incomplete plug 10, and to allow the center pin 28 to protrude into an aperture 70 formed in the center of the recess 68 in the holder 66.

When the mold 57 is loaded with the plug 10, the holder 66 rests against a vertical abutment 72 provided at one end of a mold support 74. The other end of the mold support 74 is provided with a vertical post 76 carrying a pivoted cam 78 at the upper end thereof. The cam 78 is arranged to engage and shove a pivoted plate 80 against the adjacent end of the rectangular mold 58, which action in turn thrusts the rest of mold 57 and the holder 66 against the abutment 72. In doing so, both parts of the mold 57 are forced tightly against the opposite ends of the incomplete plug 10. A pair of retainers, of which a retainer 82 is shown, are secured to the support 74 on opposite sides of the rectangular member 58, in order to align this part of the mold 57 with the rest of the mold.

The sockets 51, 52 and 53 are formed by suitably shaped prongs 84, 85 and 86, respectively (Figs. 4 and 5), which project from adjacent ends of a pair of cylinders 88 and 89. As shown in Figs. 3 and 5, the cylinders 88 and 89 are placed in end to end abutment when they are positioned in the mold cavity 62 of the rectangular mold member 58. A pair of locating pins 90-90 (Fig. 2) secure the cylinders 88 and 89 in their proper position in the mold cavity 62. The cylinder 88 carries the prong 85, and the cylinder 89 carries the prongs 84 and 86. The cylinders 88 and 89 are centrally apertured so that the center pin 28 may protrude through them and project into an aperture 91 formed in the mold cavity 62.

As shown in Fig. 4, the prongs 84, 85 and 86 are spaced 120° apart about the axis of the center pin 28. The prong 85 fits snugly against one side of the center pin 28, and it is properly dished out for such purpose. The prong 86 fits snugly against the rim of the tube 30, and this prong is similarly dished out to obtain a snug fit. The prong 84 is positioned against the inside of the rim of the shank 18, and it is suitably curved on its outer side to conform to the curvature of the shank 18.

When molten plastic is forced into the sprue hole 60 (Fig. 3) in the mold 57, it fills the space between the tube 30 and the shank 18 up to the bushing 40 to form the spacer 54. The space between the center pin 28 and the tube 30 becomes filled up to a small annular shoulder 92 located on the center pin 28, thereby forming the spacer 55 (Figs. 7 and 9). The annular shoulder 92 is engaged by the mold sections 64-64 to prevent the center pin from moving longitudinally in the aperture 70, and to seal the molten plastic within this end of the mold member 57.

The injected plastic also fills a plurality of helical grooves 94-94 formed on an intermediate portion of the center pin 28, thereby forming corresponding threads on the inner periphery of the spacer 55, which bond the center pin 28 to the spacer 55 in the completed plug 10.

The washer 34 and the bronze ring 36 are also bonded to this body of molded plastic.

After the injection molding operation has been performed in the mold 57, the washer 38 and the brass tip 26 are placed on the center pin 28 and the resulting partially molded portion of the plug 10 then has the appearance illustrated in Figs. 6 and 7. The partially completed portion of the plug 10 is then placed in a profiling machine of known type to produce the ball contact 14 and the ring contact 16, in the manner previously described.

The next step in the manufacture of the plug 10 involves the formation of a cylindrical shell 98 of plastic molded around adjacent ends of the plug 10 and the cordage 12. This operation is performed in a mold 100 (Fig. 8) having a sprue hole 102 which leads to a mold cavity 104 in the interior of the mold 100. Before the plug is placed in this mold, the tangs 50—50 are inserted into the sockets 51, 52 and 53 as shown in Figs. 8 and 9.

The plug 10 is provided with an annular shoulder 106 located on the cylindrical shank 18 near the midpoint thereof. The shoulder 106 functions as a stop when the right hand end of the plug 10, as viewed in Fig. 1, is inserted into the jack on a telephone switchboard. The molded shell 98 covers the joint between the plug 10 and the end of the cordage 12, as well as the adjacent portion of the shank 18 up to the shoulder 106. In addition, the cordage 12 is encased by the shell 98 for a distance approximately equal to the amount of the shank 18 of the plug 10 that is covered by molded plastic. The exposed portions of the conductors 43, 44 and 45, as well as the metallic bands 46—46 are completely enveloped by the molded shell 98. The shell 98 becomes an integral portion of the main body of the plug 10, and also functions as a hand grip for operators at the telephone switchboard. The end of the cordage 12 is embedded firmly in the molded shell 98, and there is no tendency for the plug 10 to become detached therefrom.

Among the plastics which may be used in the manufacture of cords embodying the invention are thermoplastics, such as nylon, polystyrene, polyethylene, and polymerized methyl methacrylate. Of these thermoplastics, nylon is preferred. In view of the brittle nature of pure polystyrene, it may be advisable to incorporate plasticizers or to employ copolymers of styrene with other synthetic resins. In the case of nylon, the high molecular weight copolymers derived from hexamethylenediamine and adipic acid are particularly useful. These thermoplastics exhibit toughness, impact resistance, light weight, ease of molding, good insulating properties, and dimensional stability over a wide range of temperatures, which properties make them outstandingly valuable in the manufacture of telephone cords. They are readily available in the form of molding powders in the commercial chemical market, and in this form they may be injected into molds in accordance with established procedures. Specific details of these procedures are readily obtainable from suppliers of such molding powders.

As a matter of convenience, the invention has been illustrated and described with reference to the specific construction of a cord designed for making connections in a three-conductor system. However, the principles of the invention are equally applicable in the construction of cords for two-conductor systems, as well as cords designed for systems employing more than three conductors. Furthermore, the construction of other component parts of the cord may be varied without departing from the spirit and scope of the invention.

What is claimed is:

1. The method of making electrical connection plugs and attaching them to an end of a cord having a plurality of insulated conductors therein, which comprises mount-

ing a conductive tube on a conductive center pin and within a conductive tube shank of a plug body in concentric spaced relationship thereby partially assembling a plug body, placing the subassembly within a mold having a plurality of arcuate shaped projections having a common radial center and being spaced from the radial center varying distances, said mold having a configuration designed to form in the interior of the plug body a mass of plastic material having a plurality of spaced arcuate sockets formed by said arcuate projections and adjacent to the shank, the tube and the center pin and having a common radial center with the radial center of said projections, the shank, the tube and the center pin, injecting plastic material into the mold to form said mass and said sockets, placing metallic terminals at the end of said cord, inserting the terminals into the arcuate sockets in frictional engagement with said shank, said tube and said center pin, respectively, to make individual electrical connections therewith, and molding plastic into a shell encasing the conductors at the end of the cord and of the adjacent portions of the cord and of the plug body.

2. A connection cord including a length of cordage having a plurality of individually insulated conductors therein, one end of said length of cordage being attached to a telephone plug including at least one conductive tube mounted concentrically in spaced relationship over a conductive center pin having a contact ball formed at one end thereof, the improvement which comprises a mass of molded plastic in situ individually insulating the center pin and each conductive tube and holding them in concentric spaced relationship, said mass of molded plastic having an arcuate-shaped socket adjacent to the center pin and each conductive tube, the sockets having a common radial center and being spaced from the radial center at varying distances, and a plurality of metal terminals at the end of said cord positioned individually in the arcuate-shaped sockets in frictional engagement and electrical contact with the center pin and each of said tubes.

3. A connection cord including a length of cordage having a plurality of individually insulated conductors therein, one end of said length of cordage being attached to a telephone plug including at least one conductive tube mounted concentrically in spaced relationship over a conductive center pin having a contact ball formed at one end thereof, the improvement which comprises a mass of molded plastic in situ individually insulating the center pin and each conductive tube and holding them in concentric spaced relationship, said mass of molded plastic having an arcuate-shaped socket adjacent to the center pin and each conductive tube, the sockets having a common radial center and being spaced from the radial center at varying distances, a plurality of metal terminals at the end of said cord positioned individually in the arcuate-shaped sockets in frictional engagement and electrical contact with the center pin and each conductive tube, and a shell of molded plastic enveloping the terminals, the conductors at the end of the length of cordage, and the adjacent portions of the cord and of the body of the telephone plug.
